L. COLWELL

Des. 144,356

SHOE OR SIMILAR ARTICLE

Filed Jan. 15, 1946

FIG. 2.

INVENTOR.
Laurence Colwell
BY H. Lee Helms
ATTORNEY.

UNITED STATES PATENT OFFICE

144,356

DESIGN FOR A SHOE OR SIMILAR ARTICLE

Laurence Colwell, New York, N. Y., assignor to Revlon Products Corporation, New York, N. Y., a corporation of New York

Application January 15, 1946, Serial No. 125,560

Term of patent 7 years

(Cl. D7—7)

To all whom it may concern:

Be it known that I, Laurence Colwell, a citizen of the United States, residing in the city and State of New York, have invented a new, original, and ornamental Design for a Shoe or Similar Article, of which the following is a specification, reference being had to the accompanying drawing, forming part thereof.

Figure 1 is a side elevational view of a shoe or similar article showing my new design, and Figure 2 is a top plan view.

I claim:

The ornamental design for a shoe or similar article, substantially as shown.

LAURENCE COLWELL.
